FIG. 4.

UNITED STATES PATENT OFFICE

WILLIAM R. AIMES AND GEORGE H. T. SCHAEFER, OF ATCHISON, KANSAS.

DISPLAY APPARATUS.

1,389,177.

Specification of Letters Patent. Patented Aug. 30, 1921.

Application filed July 19, 1919. Serial No. 312,004.

To all whom it may concern:

Be it known that we, WILLIAM R. AIMES and GEORGE H. T. SCHAEFER, citizens of the United States, residing at Atchison, in the 5 county of Atchison and State of Kansas, have invented certain new and useful Improvements in Display Apparatus, of which the following is a specification.

This invention relates to an apparatus or 10 device by means of which a live manufacturer's advertisement may be displayed, or a plurality of entertaining features, wording or illustrations and descriptions of processes of manufacture, or the like may be displayed, 15 and an object of the invention is to provide a display apparatus comprising an endless apron or belt, which travels over a plurality of guiding rollers and is moved past a displaying window, and also to provide a structure 20 controlling the movement of the endless apron or belt whereby the movement thereof will be intermittent, the said movement being arrested when each display upon the endless belt or apron is positioned directly 25 behind the display window, and also to construct the endless belt or apron of flexible material, preferably canvas, so that the designs or advertisements may be painted directly upon the canvas, or posters, photographs 30 or printed matter may be pasted or otherwise suitably attached to the apron for movement therewith, such pasting or attaching of posters, printed matter or photographs permitting the changing of the displays carried by the endless belt or apron 35 structure.

A further object of this invention is to associate a plurality of these endless belt structures in a single display cabinet, and to 40 provide means for controlling the movement of the endless belts or aprons, so that two of them will be held stationary, at all times, while the other is moving or, when more than three of the aprons are provided to 45 carry out the same ratio throughout the entire display apparatus, the said control means being arranged whereby the movement of the successive or next apron will be started immediately prior to the arresting 50 of the movement of the preceding apron or belt.

A further object of this invention is to mount the upper guiding roller of the rear-most run of the endless belt or apron so 55 that it may be swung outwardly through a door opening in the rear of the cabinet to

permit of the changing of the display upon the canvas, which features also lends the display apparatus for use as a changeable chart or blackboard, enabling the owner or 60 operator of the device to write various subject matter upon the endless belt or apron, which subject matter is subsequently exhibited during the operation of the device, thereby providing a device which is particularly 65 adapted for use by merchants, in the school room, or for political purposes.

A further object of the invention is to provide, a cabinet, which incloses the endless apron or belt, thereby protecting the advertising matter carried by the belt from 70 weather conditions, and to eliminate the tearing, blurring, or mutilating of the poster, or other matter exhibited, by the weather, and also increasing the longevity 75 of the device, while the regular appearance of the various displays behind their respective display windows, owing to the changeability will have increased attraction for the public over the stationary or permanent bill 80 boards.

Other object of the invention will appear in the following detailed description taken in connection with the accompanying drawings, forming a part of this specification, 85 and in which drawings:

Figure 1 is a front elevation of the improved display apparatus.

Fig. 2 is a vertical longitudinal section through the cabinet illustrating the displaying belts and their operating mechanisms in front elevation. 90

Fig. 3 is a vertical cross section through the display apparatus, illustrating the movement of one of the endless belts or aprons. 95

Fig. 4 is a vertical cross section through the apparatus illustrating the operating mechanism, and

Fig. 5 is an enlarged fragmentary view partly in section illustrating details of the operating mechanism and control for the movement of the endless apron or belt. 100

Referring more particularly to the drawings, wherein like characters indicate like and corresponding parts throughout the several views 10 indicates the housing or cabinet of the display apparatus which is preferably constructed so as to present an artistic appearance at its outer exhibited side or front, and this cabinet is divided into 110 a plurality of compartments 11, 12 and 13, by partitions 14, and 15. However, it is to

be understood that while three compartments are illustrated in the drawings, any desired number of these compartments may be employed, without departing from the spirit of this invention. Each of the compartments, has an opening in its front wall which carries a frame 16, having a pane or window 17 of glass or other analogous transparent material carried thereby. The frames 16, are hingedly connected to the cabinet as shown at 18 and a shield or reflector 19 extends about the edges of these frames, forming means for deflecting light rays from the illuminating lamps 20 through the window 17 upon the subject matter displayed from behind the window.

Each of the compartments 11, 12 and 13 contain an individual displaying structure comprising an endless belt 21, which travels over a plurality of upper rollers 22, 23, 24, 25 and 26 and a plurality of lower rollers 27 corresponding in number to the upper rollers. These upper rollers 22, 23, 24, 25 and 26 have radial spurs or teeth 28 formed about their peripheries at their ends, and these spurs or teeth engage through openings 29 formed along the edges of the endless belt or apron 21. These edges of the endless belt or apron 21 are reinforced by relatively narrow belts 30 which are of greater thickness than the apron 21 and preferably made of stronger material, the apron 21 preferably being made of canvas, while these side belts 30 may be leather, heavier fabric, or any analogous material to prevent the tearing thereof, by the engagement of the teeth 28 through the opening 29. The rearmost upper roller 26 is carried by a shaft 31 which is in turn supported by a frame 32. This frame 32 is pivoted upon the shaft 33 upon which the rearmost lower roller 27 is mounted. The cabinet 10 is provided with a door 34 in its rear side, which may be opened to permit the frame 32 to be swung outwardly out of the cabinet as indicated in dotted lines in Figs. 3 of the drawings, to permit access to the upwardly traveling run 35 of the rearmost portion of the endless apron or belt 21 to permit the changing of the display material thereon.

The carrying shafts 36 of the rollers 23, 24, 25 and 26 are supported by bearing rods 37 which are yieldably supported by means of springs 38, the said springs allowing 55 yieldable limited movement of the upper rollers to accommodate the expansion or contraction of the endless belt 21.

The shaft 40 which carries the front upper roller 22 has a pulley 41 mounted thereon about which the belt 42 travels. This belt 42 also travels about a pulley 43 which is carried by a shaft 44. A relatively large pulley 45 is also mounted upon the shaft 44 and has operative connection by means of 65 a belt 46 with the motor 47 which operates

the display device. This motor or prime mover 47 may be an electric motor, hand power motor or any desired type of prime mover. The pulley 41 is rotatably mounted upon the shaft 40 and carries a clutch section 48 adapted for coaction with a clutch section 49 which is feathered upon the shaft 40 and is provided with an annular channel 50 which is keyed therein, the forked end 51 of the shifting lever 52. This shifting lever 52 is pivotally supported as shown at 53 from a supporting bar 54. This supporting bar 54 is supported by the shaft 40 and the shaft 55', which carries the foremost lower roller 27. The lower end of the shifting lever 52 angles outwardly away from the supporting bar 54 and is held in engagement with the cam surface 55 of an operating wheel 56 by means of an ordinary spiral spring 57. The wheel or disk 56 is mounted upon a shaft 58 and it is provided with outstanding portions 59 upon its cam surface, which when they are brought into engagement with the lower outwardly angling end of the lever 52 will rock this lever 50 for moving the clutch section 49 into operative engagement with the clutch section 48 thereby rotating the shaft 40 and consequently the roller 42 by the rotation of the pulley 41, imparting movement to the endless apron or belt 41. When the lower end of the shifting lever 52 engaging the lower portion of the cam surface 55 the lever will be in position to pull the clutch section 49 out of operative connection with the clutch section 48 at which time the movement of the endless belt or apron 21 will be arrested. The wheel or disk 56 has a plurality of radiating arms 60 carried by its periphery which arms are engaged by arms 61 carried by the endless belt or apron 21 for partially rotating the wheels 56 during the movement of the endless belt 21 to properly operate or control the operation or movement of the endless belt to cause it to be arrested when each individual display thereof is positioned behind the window 17. The arms 61 are placed upon the belt 21 at the beginning or slightly in advance of each individual exhibit whereby movement of the belt be properly controlled.

In a multiple machine or display apparatus as illustrated in the drawings, the raised portions 59 of the cam surfaces 55 are arranged so that the operation of the various endless belts will be successive and immediately prior to the arresting of the movement or operation of the first belt, the second one will start to operating or moving for moving an individual display behind its respective window, and the third belt will remain stationary during the movement of the second belt, as will also the first belt, then when the second belt has reached a proper position for displaying a subsequent individual display, 130

the third belt will start operating to change the exhibiting display thereon, at which time the first and second belts will remain stationary. When the third belt has moved 5 sufficient to change the individual display exhibited, the raised portion 59 of the cam surface 55 of the wheel 56 thereof will have moved out of engagement with the shifting lever 52 of this unit of the mechanism allowing 10 the arresting of the movement thereof, and immediately prior to the arresting of this movement the clutch levers 52 of the first unit will have been shifted to start the operation of the first endless belt, thereby 15 one of the belts will be constantly in motion while the other two are stationary.

The foremost of the lower rollers 27 is positioned directly beneath the foremost upper rollers 22, so that the upwardly traveling 20 forward run of the endless belt or apron 21 will move vertically and stand vertically behind the window 17, and by particular reference to Fig. 3 of the drawings, it will be noted that the apron or belt travels from 25 the rearmost lower roller 27 directly to the foremost lower roller 27 and then in sinuous manner alternately about the upper and lower rollers. By providing the plurality of upper and lower rollers, the links of the apron or 30 belt may be increased, thereby providing or permitting the exhibiting of a greater number of advertisements or display subject matter behind each of the windows 17.

In operation, the shaft 44 is rotated from 35 the prime mover 47 and the pulley 41 is rotated from the shaft 44 so that when the clutch section 49 is in meshing engagement with the clutch section 48, the roller 22 will be positively rotated, and will move the endless 40 apron or belt 21 through the engagement of the seat 28 at the ends of the roller in the opening 29. Assuming that the belt 21 of the first unit of the display apparatus is moved first; when the endless belt 21 has 45 been moved sufficient distance to place an individual display unit thereon behind the window 17, the lower portion of the cam surface 55 will have moved so that the lower end of the clutch shifting lever 52 will be in 50 engagement therewith, which will allow the lever to be rocked under action of the spring 57 disconnecting the clutch sections 48 and 49 and consequently arresting movement of the endless belt 21. All of the wheels or 55 disks 56 are mounted upon the shaft 58 and the raised portions 59 of the cam surfaces thereof are arranged so that immediately prior to the operating of the lever 52 of the first unit will disconnect the two clutch sections 48 and 49 thereof, the lever 52 of the second or next unit will be operated to connect the clutch sections 48 and 49 of this unit which will start the operation of the endless belt in the second unit. The rotation of the 65 wheels or disks 56 will then be taken up and

continued by the engagement of an arm 61 carried by the belt 21 of the second unit, an arm of the belt of the first unit which was previously operating these wheels having moved out of engagement with the pin 60 70 of its respective wheel 56. After the belt 21 of the second unit has moved a sufficient distance to place an individual display unit thereof, behind its respective window 17, the operation of the device will be carried 75 to the third unit in the same manner heretofore described, and from the third unit it will be carried over to the first unit or to a fourth unit, depending upon the number of units employed in the advertising display 80 apparatus.

Changes in details may be made without departing from the spirit of this invention, but;

I claim:

1. In a display apparatus, the combination of a cabinet having a display window therein a door in the back of said cabinet, an endless belt traveling in a plurality of substantially vertical runs within said cabinet, means for moving said belt past said window, the rearmost run of said belt being pivotally supported whereby it may be moved outwardly through the door opening in the rear of said cabinet. 95

2. In a display apparatus, the combination of a cabinet having a display window therein, a door in the back of said cabinet, an endless belt traveling in a plurality of substantially vertical runs within said cabinet, means for moving said belt past said window, the rearmost run of said belt being pivotally supported whereby it may be moved outwardly through the door opening in the rear of said cabinet, and means for 100 moving said belt, and means controlling said moving means for automatically arresting movement of the belt at predetermined intervals. 105

3. In a display device, the combination of a plurality of endless belts arranged side by side, a prime mover, an operating shaft arranged transversely of the belts, means operatively connecting the operating shaft and the prime mover, an operating roller for 110 each of said belts, means operatively connecting the operating shaft with each of the rollers, said means including sliding clutches, a controlling shaft arranged transversely of the belt, operating means secured to the controlling shaft for independently operating each of said clutches, and means carried by the belts for engaging said operating means. 120

4. In a display device, the combination of a cabinet having display windows, of a plurality of endless belts carrying a plurality of individual display units adapted for display through said windows, an operating shaft arranged longitudinally of the cabinet and transversely of the belts, means for 125 130

- operating said operating shaft, an operating roller for each of said belts, a pulley disposed adjacent to each one of said rollers, clutch means for connecting the rollers to 5 each of said pulleys, a controlling shaft arranged longitudinally of the cabinet and transversely of the belts, an operating lever for each one of said clutches, a cam wheel for operating each one of the clutch levers 10 rigidly secured to said controlling shaft, radially extending pins carried by each one of said cam wheels, and outstanding arms carried by each one of said belts for engaging the arms of said cam wheels.
- 15 5. In a display device, the combination of a cabinet provided with a plurality of display windows, a plurality of endless belts for movement behind said display windows and moving in a plurality of vertical runs 20 within the cabinet, said cabinet provided with door openings in its rear sides, the rearmost pair of vertical runs of said belt being pivotally supported, whereby they may be moved outwardly through said door opening to permit access thereto.
- 25 6. In a display device, the combination of a cabinet provided with a plurality of display windows, a plurality of endless belts for movement behind said display windows, 30 and moving in a plurality of vertical runs within the cabinet, said cabinet provided with door openings in its rear sides, the rearmost pair of vertical runs of said belts being pivotally supported, whereby they 35 may be moved outwardly through said door opening to permit access thereto, means for moving said belts, means for controlling the movement of the belts whereby the belts will be intermittently moved, and control means 40 arranged to permit successive movement of the belts.
7. In a display device, the combination of a cabinet provided with a plurality of display windows, a plurality of endless belts 45 for movement behind said display windows, and moving in a plurality of vertical runs within the cabinet, said cabinet provided with door openings in its rear sides, the rearmost pair of vertical runs of said belts 50 being pivotally supported, whereby they may be moved outwardly through said door opening to permit access thereto, means for moving said belts, means for controlling the movement of the belts whereby the belts 55 will be intermittently moved, control means arranged to permit successive movement of the belts, said control means arranged whereby when one of the belts is in motion, the other will be stationary.
- 60 8. In a display device, the combination of a cabinet provided with a plurality of display windows, a plurality of endless belts for movement behind said display windows, and moving in a plurality of vertical runs 65 within the cabinet, said cabinet provided with door openings in its rear sides, the rearmost pair of vertical runs of said belts being pivotally supported, whereby they may be moved outwardly through said door opening to permit access thereto, means for moving said belts, means for controlling the movement of the belts whereby the belts will be intermittently moved, control means arranged to permit successive movement of the belts, said control means arranged whereby when one of the belts is in motion, the other will be stationary.
- 90 9. In a display device, the combination of a plurality of endless belts, an operating roller for each of said belts, a prime mover, independent means operatively connecting said prime mover and each of said rollers for moving said belts upon rotation of the 95 rollers, clutches for controlling the connection between the prime mover and each of the rollers, so that movement of the belts can be arrested for a predetermined interval, and means carried by each of the belts for operating said clutches.
- 100 10. In a display device, the combination of a plurality of endless belts, an operating roller for each of said belts, a prime mover, a clutch mechanism for establishing operative connection between each of said rollers and the prime mover, a clutch shifting lever for each of the clutches, a wheel for each of the clutches having a cam surface thereon for engaging a portion of each one of the clutch shifting levers so that the clutches will be operated during the rotation of said wheels to control the rotation of the rollers and movement of the belt, means operatively connecting the wheels together, and means 105 for rotating said wheels by said belts.
- 110 11. In a display device, the combination of an endless belt, a roller for moving said belt, a prime mover, a clutch mechanism for establishing operative connection between said roller and prime mover, a clutch shifting lever, a wheel having a cam surface thereon against which a portion of said clutch shifting lever engages, whereby the clutch will be operated during rotation of said 115 wheel to control the rotation of the roller and movement of the belt, a plurality of radiating fingers carried by said wheel, and bars carried by said belt at spaced intervals for engaging said wheel to rotate the wheel upon 120 movement of the belt.
- 120 12. In a display device, the combination of an endless belt, a roller for moving said belt, a prime mover, a clutch mechanism for establishing operative connection between said roller and prime mover, a clutch shifting lever, a wheel having a cam surface thereon against which a portion of said clutch shifting lever engages, whereby the clutch will be operated during rotation of said 125 belt.

wheel to control the rotation of the roller and movement of the belt, a plurality of radiating fingers carried by said wheels, bars carried by said belt at spaced intervals for engaging said wheel to rotate the wheel upon movement of the belt, a second endless belt, a clutch mechanism establishing communication between said second endless belt and said prime mover, a wheel having a cam surface for controlling operation of the clutch mechanism of the second belt, said last named wheel operatively connected to said first named wheel for rotation therewith, and bars carried by the said named belt for rotating the cam wheel associated therewith, said cam wheels arranged whereby when the first named belt is in motion, the second named belt will be stationary, and whereby movement will be imparted to the second named belt prior to the arresting of movement of the first named belt.

13. In a display device, the combination of an endless belt, a roller for moving said belt, a prime mover, a clutch mechanism for establishing operative connection between said roller and prime mover, a clutch shifting lever, a wheel having a cam surface thereon against which a portion of said clutch shifting lever engages, whereby the clutch will be operated during rotation of said wheel to 30 control the rotation of the roller and movement of the belt, a plurality of radiating fingers carried by said wheels, bars carried by said belt at spaced intervals for engaging said wheel to rotate the wheel upon movement of the belt, a second endless belt, a clutch mechanism establishing communication between said second endless belt and said prime mover a wheel having a cam surface for controlling operation of the clutch mechanism of the second belt, said last named wheel operatively connected to said first named wheel for rotation therewith, and bars carried by the said second named belt for rotating the cam wheels associated therewith, said cam wheels arranged whereby when the first named belt is in motion, the second named belt will be stationary, and whereby movement will be imparted to the second named belt immediately prior to the 45 arresting of movement of the first named belt, and means for tensioning said belts.

WILLIAM R. AIMES.
GEORGE H. T. SCHAEFER.
